UNITED STATES PATENT OFFICE.

ALEXANDER GABOR, OF PHILADELPHIA, PENNSYLVANIA.

SMOKE CONSUMER OR PURIFIER.

1,359,340.

Specification of Letters Patent. Patented Nov. 16, 1920.

Application filed March 29, 1918. Serial No. 225,497.

To all whom it may concern:

Be it known that I, ALEXANDER GABOR, a subject of the King of Roumania, residing at Philadelphia, in the county of Philadelphia and State of Pennsylvania, have invented certain new and useful Improvements in Smoke Consumers or Purifiers; and I do hereby declare the following to be a full, clear, and exact description of the invention, such as will enable others skilled in the art to which it appertains to make and use the same.

This invention relates to smoke consumers, and the primary object of this invention is to provide a smoke consumer structure which will remove all composite particles from the smoke or products of combustion from a stove, furnace, boiler or the like, carrying off the composite ingredients of the products of combustion, and allowing the gases to pass upwardly through a chimney for atmospherical distribution.

More specifically, the object of the invention is to provide a drum or retainer which has communication with the outlet end of the stack leading from a fire box, or furnace, in which drum are positioned a plurality of perforated water distributing drums to which relatively cool water is fed under pressure and forced through the perforation therein to co-mingle with the products of combustion and remove the solid ingredients therefrom, which composite ingredients together with the water pass upon suitable baffles within the drum and are guided to outlet pipes for delivery to a sewerage system.

With the foregoing and other objects in view, this invention consists in such novel features of construction, combination and arrangement of parts as will be hereinafter more fully described, illustrated in the accompanying drawings and claimed.

In describing the invention in detail, reference will be had to the accompanying drawings wherein like characters designate like and corresponding parts throughout the several views and in which:

Figure 1 is a vertical section through the
50 improved smoke consumer or purifier,

Fig. 2 is a horizontal section on the line

Fig. 2 of Fig. 1.

Fig. 3 is a vertical section through the water distributing drum,

55 Fig. 4 is a fragmentary vertical section

through the housing of the smoke consumer having the water distributing drums removed.

Fig. 5 is a perspective view of a modified form of the water distributing drum;

Figs. 6, 7, and 8 are vertical sections through modified forms of the water distributing drums.

Referring more particularly to the drawings, 1 designates the stack or chimney leading from a fire box, furnace or other suitable device in which a fire is built. The products of combustion of the fire pass through the stack or chimney 1 into the housing 2 of the smoke consumer or purifier structure which housing is supported by a suitable supporting structure 3. The housing 2 is substantially compound-conical in shape, having an annular flange 4 formed about the center thereof which flange rests upon the horizontal portion 5 of the support 3. The upper portion 6 of the housing 2 projects above the supporting structure 3 and is provided with an opening, which is closed by a suitable slidable door structure 7. A stack 8 communicates with the upper end of the upper portion 6 to permit of the passage of the gases of the products of combustion upwardly therethrough for atmospheric distribution.

The lower portion 9 of the housing 2 extends downwardly into the supporting structure 3 and it has a plurality of baffles 10 formed thereon which baffles are circular in plan, and have their walls inclining inwardly toward the central axis of the housing 2 as clearly shown in Figs. 1 and 4 of the drawings, to provide pockets 11 exteriorly of the baffle plate and between the outer surfaces of the baffle plate and the inner surfaces of the adjacent portions of the section 9. Openings 12 communicate with the lowermost portion of the pocket 11 and branch pipes 13 extend through these openings having communication with the pocket and with pipes 14. The pipes 14 extend downwardly along the outer surface of the lower portion 9 of the housing 2 and all communicate with a main drain or outlet pipe 15 which may lead into a sewerage system or into any similar place as desired.

tem or any other similar place as desired. A water distributing drum structure generically indicated by the numeral 16 is positioned within the housing 2 and it comprises a plurality of drums 17, 18, and 19.

arranged one above the other and each drum being slightly smaller in diameter than the one next thereabove as clearly shown in Figs. 1 and 3 of the drawing. The 5 drums 17, 18, and 19 have the lower angular portions 20 of their walls provided with a plurality of relatively small perforations 21. A pipe 22 is connected to the uppermost drum 17 and it is detachably connect- 10 ed to a water feed pipe or hose 22' which may have communication with a water storage tank, a water main or any other suitable structure which will force water there- 15 through under pressure. The pipe 22 projects downwardly within the water distributing drum 17 and has its lower end flared outwardly as shown at 23. A pipe 24 is positioned within the pipe 22, and is threadably connected to a flange 25 formed 20 in the bottom 26 of the drum 17. The pipe 24 is formed upon or is suitably connected to the uppermost portion of the drum 18 for feeding water to this drum. A third pipe 27 is positioned within the pipe 24 and 25 it extends downwardly through this pipe, and through the drum 18 having its lower end connected to a collar 28 formed upon the base 29 of the drum 18. A pipe 30 which is formed upon the drum 19 is also 30 connected to the flange 28 so that water passing downwardly through the pipe 27 will enter and pass through the pipe 30 into the drum 19. The base 31 of the drum 19 is concavo-convex, projecting upwardly into 35 the drum as clearly shown in Fig. 3 of the drawing for deflecting laterally the water which enters the drum from the pipe 30. The lower end of the pipe 30 which projects into the drum is flared outwardly as shown 40 at 32 to prevent back or upward pressure of the water within the drum.

The water enters the various drums 17, 18, and 19 under pressure and is forced through the perforations 21 in relatively fine 45 streams which mingle with the products of combustion which enter the housing 2 from the chimney or stack 1. The relatively fine streams of water passing through and intermingling with the products of combus- 50 tion will carry the solid ingredient of the products of combustion downwardly there- with into the pocket 11, and out of these pockets through the branch pipe 13 into the pipes 14 and outwardly through the 55 drain pipe 15.

In Fig. 5 of the drawing, a modified form of the water distributing drums is illustrated.

In this form, the drums 17^a, 18^a, and 19^a 60 form portions of spheres, and are provided with perforations 21^a arranged annularly about the drum between their uppermost portions and their lowermost edges. The sides of the drums 17^a, 18^a, and 19^a curve 65 upwardly, as shown in the section through

the drum 17^a, illustrated in Fig. 6 of the drawing, and form the bottom for the drum. The bottoms of the drums 17^a and 18^a terminate in internally threaded flanges 25^a to which the various pipes which extend 70 through the drum are attached to properly hold these pipes in their relative position and permit the passage of the water under pressure to the various drums.

In Fig. 7 of the drawing, a further modified form of the water distributing drums is shown. This drum structure which is indicated by the numeral 17^b is similar in construction to the drums 17, 18, and 19, differing from these drums in that the bot- 80 tom 26^b curves upwardly and inwardly, in lieu of extending angularly upwardly and inwardly. The bottom terminates in a centrally disposed internally screw threaded flange 25^b. An upstanding flange 27^b is 85 formed integrally with the upper portion of the drum 17^b and it is externally and internally screw threaded as shown at 28^b for connection with the various feed water pipes. The lower portion 20^b of the drum 90 17^b is provided with a plurality of perforations 21^b through which the water egresses.

In Fig. 8, the modified water distributing drums indicated by the numeral 19^c is substantially egg-shaped, except that the bot- 95 tom 31^c thereof is concavo-convexly formed, extending upwardly into the center of the body of the drum to provide a deflector for deflecting the water toward the perforations 21^c thereof. The body of the drum 19^c has 100 a pipe section 27^c formed thereon a portion of which projects downwardly into the body and has its lower terminal flared outwardly as shown at 32^c for assisting the bulged inwardly portion of the bottom 31^c in prop- 105 erly guiding the water through the perforation 21^c. The portion of the pipe 27^c which projects outwardly above the body of the drum 19^c is externally and internally screw threaded, being externally screw 110 threaded for connection with the flange formed in the bottom of the drum next thereabove and internally screw threaded for connection with the pipe 28^c which supplies the water to this drum structure. 115

It should be noted that by having the drums reduced in size as shown in Figs. 1 and 2 the drums will produce a wedge shaped structure which will be engaged by the smoke passing through the pipe 1 and 120 therefore this smoke will be divided into a hollow or circular curtain thus permitting the water spray from the drum to very effectively pass through all of the smoke. The smoke will therefore be very efficiently 125 acted upon by the water and the solid matter in the smoke will be removed. By having lower or inner end portions of the pipes 16, 30 and 27^c flared as shown at 23, 32 and 32^c respectively the water will be guided in 130

its passage through the drum and thus pass out evenly through the opening formed in the drum. This will produce a very efficient spray which will act very efficiently on the 5 smoke.

In reducing the invention to practice, certain minor features of construction, combination and arrangement of parts may necessitate alteration to which the patentee 10 is entitled provided such alterations are comprehended within the scope of what is claimed.

What is claimed is:

1. In a device as set forth, a housing, a 15 plurality of baffle plates positioned within said housing and coacting with the walls of the housing to form pockets, outlet pipes communicating with said pockets, drums positioned within said housing in super- 20 posed relation and tapered to provide a smoke separating wedge, the drums being provided with a plurality of relatively fine perforations, positioned for directing the streams of water into said pockets, and 25 means for communicating with said drums

for feeding water under pressure to the drums.

2. In a device as set forth, a retaining housing having a plurality of baffles formed integrally therewith and inclining inwardly 30 toward the central axis of the housing, said baffles coacting with the walls of the housing to form pockets, the pockets being provided with water outlets, a plurality of drums positioned within said housing in 35 superimposed relation and provided with a plurality of relatively small perforations to deflect water through the housing into said pockets, the drums being positioned above their respective troughs and tapered to provide a smoke dividing wedge and means 40 for feeding water to said water distributing drums.

In testimony whereof I affix my signature in presence of two witnesses.

ALEXANDER GABOR de VOYLA.
